CONVEYOR FLIGHT CONSTRUCTION

Alfred W. Gardes, Lebanon, Ind., assignor to Indiana Commercial Filters Corporation, a corporation of Indiana

Application March 19, 1953, Serial No. 343,455

1 Claim. (Cl. 198—176)

This invention relates to improvements in a conveyor flight construction, and more particularly to a flight construction highly desirable for use in connection with a tension member such as a chain or cable to operate inside a pipe or tube to convey material through the tube, although the invention may have other uses and purposes as will be apparent to one skilled in the art.

Pipe and tube conveyors are utilized for transporting many types of solid or fibrous material which will settle to the bottom of tanks, hoppers, or other types of reservoirs, and this material may be either wet or dry. By way of example, such conveyors may be used to handle cast iron dust, other metallic dust and chips, abrasive sludge, metallic scale, and the like, from metal working machines, such dust and chips being usually mixed with the coolant utilized with such machines. In other instances, the conveyor may handle grain, soaps and soap powders and chips, sludge, dirt and dust, tankage, cracklings, etc.

Heretofore the construction of flight conveyors to operate in pipes or tubes, and in some instances in open troughs, usually included a flexible propelling element or assembly in the form of a chain or cable with transverse flights positioned at spaced intervals therealong. In many cases, the flights comprised resilient disks backed up by metal plates disposed against the flat faces of the disks. In substantially all instances, the flights were provided with some form of opening through which the propelling element or assembly extended. In some instances the opening was in the form of a notch leading inward from the circumference of the disk in one region, while in other cases the opening was in the form of an aperture through the disk. In either case, and particularly with the latter case, extreme difficulty was experienced owing to undue wear of the flight by contact with the inside of the pipe or tube especially when the conveyor passed around a bend, and the propelling element naturally endeavoring to assume the shortest path of travel would forcefully cause a rubbing of the under portion of the flight against the inside of the pipe or tube thereby injuring the flight. This was particularly true when material of a highly abrasive character was being conveyed.

With the foregoing in mind, it is an important object of the instant invention to provide a conveyor of the type operable in a pipe, tube, or open trough, equipped with a resilient flight construction so arranged that the resilient flight itself will not come in contact with the pipe or tube even though the conveyor must turn corners or pass around bends in the tube or channel.

Another object of the invention is the provision of a conveyor of the character set forth herein, embodying resilient flights with backing means in the form of lugs covering a portion of a flat face of the flight, and extending underneath the lower edge of the flight to ride the trough or tube in which the conveyor is operable.

Still another feature of the invention resides in the provision of a conveyor flight assembly embodying a resilient flight in the form of a disk with a segment re-

2

moved in the location corresponding to the bottom of the flight with respect to the propelling means and tube or trough with which the flight is associated.

Still a further feature of the invention resides in the provision of a flight conveyor embodying resilient disk-like flights with backing means therefor bearing against a flat face of the flight, and extending underneath the flat portion of a flight where a segment has been removed.

It is also a feature of the invention to provide a conveyor flight assembly embodying resilient disk-like flights, each flight being made up of two separate pieces securely held in position between metallic plate means, with the means on one side of the flight so constructed as to prevent contact of the flight itself with that through which the conveyor travels.

Still another feature of the invention resides in the provision of a conveyor flight assembly, wherein backing means are used of such construction as to lend support to one edge portion of a flight, as well as a flat face of the flight.

Still another object of the invention resides in the provision of a flexible conveyor embodying transverse resilient flights, the conveyor being so constructed that the flights will not contact the wall of a tube or trough in which the conveyor operates, regardless of the turning or twisting of the propelling means, especially when passing around corners or bends in the overall conveying assembly.

While some of the more salient features, characteristics and advantages of the instant invention have been above pointed out, others will become apparent from the following disclosures, taken in conjunction with the accompanying drawing, in which—

Figure 1 is a diagrammatic or schematic illustration of a pipe or tube conveying system to illustrate a use for the instant invention;

Figure 2 is a fragmentary sectional view through a bend of the pipe or tube embodied in the system, illustrating the conveyor itself in side elevation;

Figure 3 is an enlarged transverse sectional view taken substantially as indicated by the line III—III of Fig. 2, looking in the direction of the arrows; and

Figure 4 is a fragmentary bottom plan view of a single flight assembly.

As shown on the drawings:

By way of example and not by way of limitation, the illustrated embodiment of the instant invention may be utilized in the system diagrammatically illustrated in Fig. 1. This system includes a loading hopper 1 of any suitable character, and a pipe or tube 2 which extends downwardly from a discharge housing 3 through the loading hopper 1, upwardly and back to the discharge housing. Inside the discharge housing, the tube is open, and the conveyor itself passes around a sprocket, thereby unloading the material conveyed into a chute 4 where it may gravitate into any suitable receptacle. Inside the loading hopper 1, the pipe or tube is cut away at the top portion as indicated at 5 so that in that region it is in the form of an open trough and material readily falls into the pipe tube to be carried therealong by the conveyor to be later described. It will be noted that the pipe has bends therein, and particular reference is made to a bend of the character indicated at 6 in the upper right-hand portion of the figure, since Fig. 2 of the drawings is illustrative of the conveyor passing around that particular bend, with the illustration, for convenience, being rotated 90° to the left from the showing in Fig. 1.

The tube or pipe 2 obviously is fabricated from several different lengths, connected together at intervals with the aid of laterally extending flanges 7 as indicated in Fig. 2.

With reference now to Figs. 2, 3 and 4 of the draw-

ings, it will be seen that the conveyor itself comprises a propelling element or assembly which in the illustrated instance is in the form of a forged chain, including a pair of outer links 8—8 pivotally connected to each end of a single inner link 9, and so on. The illustrated chain is of substantially the same character and construction as the chain disclosed in J. H. Weston Patent No. 870,704, issued November 12, 1907.

At any desired locations along the chain flight assemblies are provided. The spacing between the flight assemblies may be made as great as needed consistent with the material to be conveyed, and in the illustrated instance I have shown a flight assembly mounted on each inner link 9.

Each flight assembly comprises a resilient disk-like flight 10, preferably slightly less in diameter than the inside diameter of the pipe 2, so that the flight does not contact the inner wall of the pipe. This lack of contact does not interfere with the conveying of material through the pipe, since the action is continuous. Each flight is cut off along a straight line at the bottom portion thereof as indicated at 11 in Figs. 3 and 4, so that a segment of the flight is actually removed. In the center of the straight line bottom edge, an upwardly extending square or rectangular shaped notch is provided as indicated at 12 to accommodate an inner link 9 of the chain, as well as lugs on a backing means later to be described.

Each resilient flight 10 may be made of any suitable material, and in some cases the flight does not even have to be resilient, although that is preferable in most cases. In some instances, as well, the material of the flight will be governed by the chemical ingredients of the material being conveyed so as to avoid the development of any adverse reactions. Usually, however, a flight made of an oilproof synthetic rubber or the equivalent is highly satisfactory.

The illustrated embodiment of the instant invention is a conveyor designed to carry heavier loads such as cast iron dust and chips, other metallic cuttings, sludge, and the like. Such a conveyor is usually operated in one direction, whereas conveyors of this type for lighter substances may be constructed somewhat differently to operate in either direction at will. The instant conveyor, looking at Fig. 2, moves in a clockwise direction around the bend in the tube 2. The leading side of each flight is preferably reinforced by means of a metallic plate 13, such as a stamping, and this plate is of course notched as indicated at 14 in Fig. 4 in order to accommodate the chain passing therethrough. The plate as clearly seen in Fig. 2 is not of as great a diameter as the flight, so that the flight projects beyond the plate in all directions except at the bottom.

Heavier supporting means are provided on the trailing side of each flight in the nature of backing means. These backing means are commonly referred to as a backing plate, but actually comprise a pair of allochiral members or half plates 15 and 16 in the form of brackets. Each of these backing members has a backing plate portion 17, of the general shape, but of lesser size, than half the flight 10, as clearly seen in Fig. 3. On the inner margin of each backing member is a rearwardly extending flange 18 the upper portion of which slopes rearwardly, and the lower portion of which has a straight edge, as seen best in Fig. 2. On the lower portion of this flange, there is an inwardly extending lug 19, Fig. 3, which enters between the sides of the inner link 9. A bolt 20 extends through the flanges 18—18 and the lugs 19—19 and the inner link 9 of the chain, as clearly seen in Fig. 3, to firmly join each flight assembly to the chain. With reference now to Figs. 2 and 4, it will be noted that the flight cannot slide longitudinally of the chain to any material extent, because it will reach the end of its respective inner link 9.

The flight 10 is provided with a pair of holes laterally

spaced in the upper portion, to accommodate bolts 21 each of which extends through the front reinforcing plate 13, the flight, and the plate portion 17 of the respective backing member 15 or 16. Thus the flight is positively held in position.

An important feature of the instant invention is the provision of forwardly extending lugs 22 on the bottom of each backing member 15 or 16. As seen clearly in Figs. 2 and 3, these lugs are substantially triangular in cross section, and extend forwardly to underlie and lend support to a portion of the flat edge of the flight 10 where it is cut off at 11. Thus, not only does the backing member support and reinforce the rear face of the flight 10, but it also functions as a rest for the bottom flight edge portion of the flight. Now, as seen clearly at 23—23 in Fig. 3, it is the lugs 22—22 that ride the inside surface of the pipe or tube 2. This arrangement eliminates contact of the flight 10 with the inside surface of the pipe. The backing members 15 and 16 are preferably cast or equivalently formed in a single piece including the plate portion 17, the flange 18, the inwardly extending lug 19, and the tube riding lug 22. The lugs may be made of cast steel or some other metal, preferably a metal having a low coefficient of sliding friction and adequate durability so that the lugs 22—22 will not wear off except by very long usage.

In operation, the instant invention is extremely simple. It will be noted that in respect to the flights the chain is eccentrically disposed, that is the chain is mainly below the horizontal diameter of the flight. Of course, while riding in the tube and turning around bends therein, the chain will tend to follow the shortest path, so that in passing through the loading hopper 1 in Fig. 1, the chain will be uppermost and the flights extending therebelow. Because of that condition, it makes no difference that there is a space between the chain and the tube between the lugs 22—22, as seen in Fig. 3. The conveying is mainly done by the flight on the opposite side of the conveyor structure. No matter whether the chain is passing around corners or bends in the pipe, or if the chain is being twisted around its longitudinal axis as would occur between the bend 6 in Fig. 1 and the bend leading up to the housing 3, the flight itself never contacts the inside pipe wall. The lugs 22 contact and ride the inside pipe wall and thus the flight 10 is very long lived since it is not deteriorated by wall contact during its substantially continuous travel.

Assuming that it is necessary for some reason to replace a flight, it is a simple expedient to remove the two bolts 21—21, and pull out the flight from between the reinforcing plate 13 and the backing means. A new flight may be slipped into position, and the bolts replaced. It is not even necessary to separate the backing means from the inner chain link 9.

In some cases, it may be deemed more expedient and more economical to have separate flight sections and to this end I have illustrated a line 24 sloping through the upper solid portion of the flight from the circumferential edge to the aforesaid notch 12, dividing the flight into two pieces. With this arrangement, removal and replacement of the flight may be somewhat facilitated, but also it may only be necessary to replace one section of the flight. This is an additional feature that may be incorporated, if desired, but in many cases the flight will simply be made of a one piece construction as previously described.

From the foregoing it is apparent that I have provided a novel and highly durable form of conveyor for use in a pipe, tube, open top channel, or the like. The structure is simple, easily repaired, and the flight itself does not come in contact with the inside face of the tube or pipe, even when rounding corners or even when the conveyor is twisted about its longitudinal axis. Consequently, the structure is extremely long lived and therefore highly economical.

It will be understood that modifications and variations may be effected without departing from the scope of the novel concepts of the present invention.

I claim as my invention:

A flight assembly for a conveyor, including a flight of a generally disk shape with a segment removed to provide a straight bottom edge portion, and backing means secured to said flight and covering a part of a flat face of the flight, and means on said backing means extending under said straight flight edge to function as a seat for the same, said flight being notched inwardly from the straight edge for propelling means to extend through the flight.
